UNITED STATES PATENT OFFICE.

JACOB B. CURRIER, OF LOWELL, MASSACHUSETTS.

APPARATUS FOR ARRANGING AND COUNTING VOTES.

SPECIFICATION forming part of Letters Patent No. 469,039, dated February 16, 1892.

Application filed June 6, 1891. Serial No. 395,376. (No model.)

To all whom it may concern:

Be it known that I, JACOB B. CURRIER, of Lowell, in the county of Middlesex and State of Massachusetts, have invented a new and 5 useful Improvement in Apparatus for Arranging and Counting Votes, of which the following is a specification.

My invention relates to mechanism for arranging ballots preparatory to counting the 10 votes with what is known as the "Australian system" of ballots; and it consists in new and useful improvements in such apparatus, whereby the ballots may be arranged rapidly and certainly according to my system of printing and arranging such ballots contained in 15 my application for Letters Patent, Serial No. 339,035, filed February 3, 1890, all substantially as hereinafter described and claimed.

In the use of the Australian system of ballots the voter makes an X-mark in a reserved 20 space at the right-hand end of the line containing the name of the candidate to be voted for. By my system, as disclosed in said former application, the ballots were so printed 25 that when opened they formed two inside pages opposite to or succeeding each other in ordinary book form, having at the right-hand end of the line on each page precisely the same breadth of space for the X-mark and 30 the same margin, if any, to the right of that. The ballots were then re-folded backward, so as to bring the two pages on the outside of the ballot, the re-folding line being precisely 35 the same as the line of the first folding, which concealed the faces of the ballot containing 40 the names of the candidates when they were first folded to be voted. It has been found expedient to have assistants or clerks prepare the ballots in packages ready to be counted 45 by the sworn officials who are to perform that duty, so that they may count the votes on the ballots more rapidly and certainly. The importance of having assistants do this work is evident when it is understood that a reasonable 50 number of sworn enumerators of the ballots are unable to count the votes on them as fast as a precinct of fifteen hundred voters will cast them unless some such method of assorting them in packages can be adopted 55 and economically practiced. It is further found to be desirable in assorting the ballots into packages that the clerks or assistants

shall have some mechanical devices to expedite their work with my improved form of ballots, and these mechanical devices are the 55 subject of this application.

In the drawings, Figure 1 represents a board and clamp in face view on which the ballots are shown to be assembled in packages by the clerk or assistant preparatory to 60 the votes being counted by the sworn enumerators. Fig. 2 represents a face view of the assembling-board, with the clamp removed. Fig. 3 is an enlarged horizontal section of part of the board on the line $z z$ of Fig. 2. Fig. 4 65 is an enlarged transverse section of part of the board on line $x x$ of Figs. 1 and 2. Fig. 5 is a rear view of the clamp and the ballots in it when removed from the board. Fig. 6 is an edge view of a portion of the clamp re- 70 moved from the board and opened ready to receive the ballots. Fig. 7 is an end view of the same. Fig. 8 is an edge view of Fig. 6 with the clamp closed. Fig. 9 is an end view of the same. Fig. 10 is an enlarged view of 75 a portion of Fig. 8 with the turn-button attached, which locks the clamp. Fig. 11 is a top plan view of the same.

A is an assembling-board made of any suitable material, but wood is preferable. This 80 board has sunk into its surface along its top edge a slot or groove a of the proper size to receive the clamp which is to hold the ballots. Extending transversely inward and at a substantially right angle to this slot a are 85 a series of grooves a^2 cut in the surface of the board. These grooves are made beveled downward on one side and with a straight vertical wall on the other side, and their function is to guide the assembling of the ballots 90 on the board in packages in the clamp. The distance apart of the vertical sides of the slot a^2 is exactly equal to the width of the edge of the ballot containing the X-marks of the voters, which is to be left exposed in the package, as shown in Figs. 1 and 5, in order that 95 the votes may be counted by the sworn enumerators. When, therefore, the ballots are successively brought against the vertical edges of the slots a^2 , with their upper edges 100 extending within the open jaws of the clamp, hereinafter described, the ballots being laid one over the other, the proper exposure of the edge of each ballot in the package will

be automatically made by the guiding vertical edge of the groove a^2 , in which the succeeding ballot is laid to make up the package. The names of candidates and designations 5 of them printed upon each ballot are precisely the same as those of every other ballot, and arranged in precisely the same space and order on the pages B B² B³ B⁴ B⁵, representing five ballots placed together by the 10 assistant in the form of a package. In placing these ballots on the assembling-board A the first ballot B⁵ is laid upon the board with its upper end in the open jaws C' and c of the clamp C and having its left-hand 15 edge bearing against the vertical wall of the right-hand slot a^2 in the board. This trues the ballot on the board and in the clamp, and does it with great exactness, because the guiding vertical wall of the slot a^2 bears upon 20 the long edge of the ballot, and the operator has only to press that edge of the ballot into the slot and against the vertical wall, which is quickly done. The next ballot B⁴ is laid on the first one and brought to place by pressing 25 its left-hand edge against the vertical wall of the next slot a^2 , and so on successively, until the last ballot B is reached, which forms the upper one of the package as made up on the board. The hinged jaw c of the clamp, which 30 is supported upon its body by the hinges c², is then closed down over the upper end of the ballots in the package and the turn-buttons c³ are swung over it, clamping the ballots firmly in the package as arranged on the board. These 35 turn-buttons c³ are set at such a pitch that they bite or press harder on the movable jaw c of the clamp as they are swung further over it, and they will thus, by turning them farther or less, hold a package of ballots, varying from 40 two to ten, with equal firmness in the clamp. The effect of this arrangement is that when the clamp is removed from the board A, as shown in Fig. 5, the full face of the ballot B⁵ on the opposite side will be exposed and the corresponding X-marks of all the other ballots B 45 B² B³ B⁴, so that by this single operation of assembling the ballots into the packages the votes for two sets of officers on the opposite pages of the ballot are exposed ready for 50 counting, one set on the exposed face, as shown in Fig. 1, and the other set on the exposed face, as shown in Fig. 5.

In counting the votes, the sworn enumerator merely reads the name of the candidate 55 on the face of the fully-exposed ballot and

runs his eye along the same horizontal line on that and the exposed X-marked edges of all the other ballots and counts up the number of X-marks on that line opposite the name of the candidate, which indicate the number 60 of votes cast for him. By these appliances the sworn enumerators are saved the trouble of turning over and looking at the full face of each ballot to determine the number of votes on it for the several candidates, and 65 one assistant and one sworn enumerator can perform the work of several enumerators by that other method, and by my method there is far less opportunity for making mistakes in enumerating the votes for each candidate 70 than by the ordinary method.

It will be evident that by this apparatus ballots may be assembled and counted which are printed upon only one face or page with a proper exposed margin for the X-mark, substantially, for instance, as shown in the ballot in Fig. 1; but usually the number of candidates at an election requires the use of two 75 pages of the ballot.

What I claim as new and of my invention 80 is—

1. The assembling-board A, provided with the slot a near one edge and the series of transverse grooves a^2 a^3 , arranged at equal distances apart and having one wall vertical 85 and the other wall and bottom inclined from the surface of the board downward to meet the vertical wall, substantially as described.

2. The combination of the board A, provided with the slot a near one edge and the 90 series of transverse grooves a^2 a^3 , arranged at equal distances apart and having one wall vertical and the other wall and bottom inclined from the surface of the board downward to meet the vertical wall, and the clamp 95 C, arranged to fit into the slot a and provided with jaws adapted to receive the ends of the ballots as they are brought to place in it by means of the slots a^2 , substantially as described. 100

3. The clamp C, provided with a fixed jaw and a hinged jaw, in combination with the turn-buttons c³, having their axes turned or pitched so as to bind the hinged jaw closer to its opposite jaw as they are turned farther 105 over it, substantially as described.

JACOB B. CURRIER.
